PREPARATION OF BREAK-FREE
GLYCERIDE OILS

Roger M. Christenson, Milwaukee, Wis., assignor
to Pittsburgh Plate Glass Company, Allegheny
County, Pa., a corporation of Pennsylvania

No Drawing. Application August 31, 1948,
Serial No. 47,130

13 Claims. (Cl. 260—425)

1

The present invention relates to the refining of crude or but partially refined glyceride oils such as soybean oil, linseed oil, cottonseed oil, corn oil or the like and it has particular relation to the refining of such oils for purposes of removing the break constituents therefrom.

One object of the invention is to provide a process of treating glyceride oils of the foregoing types for purposes of removing or transforming break constituents which process is accompanied by but slight losses of the constituents desirable in the oil.

A second object of the invention is to provide a process of treating glyceride oils containing break constituents, or other objectionable constituents in order to eliminate such constituents or render them innocuous, which can be effected in a minimum of time with a minimum of apparatus and in which there is but little or no degradation of the oil treated.

A third object of the invention is to provide a process of treating glyceride oils containing break or gum constituents to obtain a product which without substantial loss of glycerides, can be employed for such purpose as the formation of alkyd type resins or for further extraction with selected polar solvents in order to fractionate the oil into highly unsaturated and highly saturated portions of light color.

A fourth object of the invention is to provide a process of treating crude oil containing break constituents such as lecithin or similar phosphatides and coloring matter to provide without substantial loss of glycerides, a product which can then easily be bleached for purposes of removing or otherwise eliminating the color constituents therefrom.

These and other objects of the invention will be apparent from consideration of the following specification and the appended claims.

Glyceride oils such as soybean oil, linseed oil, cottonseed oil, corn oil and the like as obtained by conventional methods of removal from the seeds constituting the source thereof, include various constituents such as gums or break constituents which have a tendency to separate out and form a flock, especially when the oil is heated. The oil also usually includes other objectionable materials such as coloring matter. For some purposes and with some grades of oil, these latter constituents may not be particularly objectionable. However, if an oil of light color is required, they may require treatment in order to effect removal thereof.

The conventional test for break is known as

2

the Gardner test. It comprises adding a few drops of aqueous hydrochloric acid and heating the oil to 550° F. Formation of a precipitate is a positive test. The precipitate may be filtered off, washed free of oil with carbon tetrachloride and weighed to determine percent of Gardner break. The method is known as A. O. C. S. Official Method Ca 10—40.

The conventional method of treating glyceride oils in order to remove break and to improve the coloring involved, most usually treatment with a strong alkali such as sodium hydroxide in considerable quantities, or by degumming with water. The alkali reacts with the free fatty acids, the break constituents and to some extent with the glycerides, producing soaps which by appropriate cooling and settling technique can be collected as an under layer called foots. The foots and the oil in conventional practise are separated by decantation, centrifugation or other appropriate technique. With the foots, is entrapped considerable amounts of good oil. The foots or by-product can be sold only at a greatly reduced price.

Simple degumming, or treatment with water may also be employed to refine the oil, but it results in losses and does not completely remove the break. The break is a poison for lead catalysts employed in formation of alkyd resins.

The present invention is based upon the discovery that when glyceride oils are treated with an alkali such as sodium hydroxide, sodium carbonate, sodium bicarbonate or the corresponding potassium compounds in order partially to decompose such break forming constituents as lecithin or other phosphatides occurring in the natural or crude oil, they form products which can then be successfully neutralized with an acid such as sulfuric acid, hydrochloric acid, phosphoric acid or organic acids such as acetic acid, maleic acid or the like to provide a break free oil.

The behavior of the break constituents can be explained upon the theory that phosphatides such as lecithin split either between the glycerol nucleus and the phosphoric acid radical or between the latter radical and the basic group, e. g. choline or ethanolamine. It may be that the split in some instances will be at one position and in other instances it will be at the other, so that there will be a mixture of the two types of products in the oil. Subsequently, the oil can be dried to eliminate water and to precipitate the salts of the alkali in a form in which they can easily be filtered out. Alternatively, the salts of

the alkali and perhaps choline and the acid may be washed out by treating the oil with water and finally drying the oil by blowing it with inert gas, e. g. CO₂.

The salts, if filtered out, may further be washed with a solvent such as naphtha designed to extract out the glycerides which may be absorbed in or cling to the salts. By such treatment, practically all of the oil is recovered. The recovered portion may be returned to the oil or may be added to the next batch as desired. The usual separation of degraded products from the main body of the oil is thus avoided and refining losses are cut to a minimum.

In the practice of the invention, an oil containing gum or break constituents, such as a whole soybean oil, corn oil, linseed oil or cottonseed oil, or a raffinate oil obtained by furfural extraction of a glyceride oil as described in U. S. Patent 2,200,391, is treated with alkaline material preferably in the form of a water solution. The amount should be comparatively low, and may, for example, be within a range of from .01 to 1.00% solid alkali added as a solution per pound of oil.

The mixture of oil and alkali solution preferably, are agitated together for sufficient time to permit adequate reaction of the constituents therein. This reaction may be promoted by heating the mixture moderately during the agitation, for example, to a temperature of 50 to 100° C. Agitation may be continued as long as desired but, of course, there is no point in continuing it excessively long, since such operation merely ties up the apparatus, occupies the time of the operator and is power consuming. Usually, a period of twenty minutes to one hour is sufficient.

After the mixture has been sufficiently agitated to obtain adequate reaction between the alkaline material and the break constituents of the oil, acids should be added to neutralize the alkali. For this purpose, phosphoric acid, sulfuric acid, hydrochloric acid or organic acids such as acetic, maleic or fumaric or other acid capable of decomposing fatty acid soaps may be employed. The amount should be sufficient, or slightly in excess of the amount required approximately to neutralize any free alkali and to decompose the alkali salts in the solution. The correct amount, of course, can easily be calculated from the amount of alkali added or, if preferred, by titration of samples of the oil from time to time as acid is added.

As previously stated, removal of the alkali salt can be effected either by drying the oil and thus precipitating the salts so that they can be filtered out, or by washing the oil with water in order to extract out the salts. The oil should be dried after acidification or after washing with water, for example, by bubbling inert gas such as carbon dioxide or nitrogen therethrough at an appropriate temperature, e. g. 100 to 200° C. Lower temperatures can be employed but the removal of the water is then slower. Also vacuum could be applied to hasten the drying operation at a moderate temperature.

After the salts have been removed, the oil product as obtained, is only slightly higher in acid value than the original oil. Doubtless, it contains nearly all of the fatty acids and glycerides with which it started so that refining losses are no more than a few tenths of a percent, yet it is perfectly satisfactory for most uses to which the oils are conventionally applied, e. g. as modifiers of, or raw materials for alkyd resins for use in

coating compositions. In the latter, it does not poison the catalyst. The oil may also be subjected to further treatment as, for example, solvent fractionation as above described. If treatment with alkali then with acid, without further treatment is employed, the coloring of the oil will be about the same as that of the original oil. If lighter products are desired, the break free product as obtained by the application of the foregoing technique, is excellently adapted for simple bleaching operations. For example, the treated oil can be admixed with 1 to 5% of fuller's earth or acid activated bleaching clay, e. g. acid treated bentonite, or with activated charcoal such as bone char or other bleaching agents and the decolorizing agents filtered out to obtain oil of very light color. The bleaching agent, of course, will carry out a certain amount of oil absorbed or adherent thereto. This oil can easily be recovered by extraction with naphtha and evaporation of the naphtha therefrom. The oil recovered from the bleaching agent in this manner is not of excessively dark color and can be added to the next batch or the parent batch if desired.

The following examples are illustrative of specific applications of the principles of the invention.

Example 1

One hundred parts of partially degummed soybean oil (—24% free fatty acids, 10.5 Gardner color, 133.5 I. V.) was treated with 1.7 parts of 8% sodium hydroxide solution at 25° C. for 30 minutes and at 65° C. for 30 minutes. Enough phosphoric acid (0.136 part) was added to neutralize the alkali used and the mixture heated to 110° C. and dried by bubbling inert gas. Two parts of an acid activated bleaching earth was added and agitation continued for 30 minutes. The filtered oil had a free fatty acid content of 0.36, a negative Gardner break test, and a Gardner color of 4. The oil readily underwent an alcoholysis with glycerol with litharge as a catalyst, indicating that the break had been transformed to an innocuous form. The oil loss including that on the spent clay was 1.50%, but if the oil on the clay were recovered with naphtha, the loss was only 0.177%.

Example 2

One hundred parts of crude linseed oil (0.88% free fatty acids, 11 Gardner color, 177.0 I. V.) and giving a positive break test, was stirred with 5.9 parts of 8% alkali for 30 minutes, then heated to 65° C. A 15% solution of sulfuric acid, 5.46 parts, was added and the mixture stirred and heated to 110° C. Four parts of bleaching earth was added and the temperature allowed to fall to 75° C. where it was held until 30 minutes from the addition of earth had elapsed. The oil was then filtered to yield a product having a fatty acid content of 1.90%, a negative Gardner break test, and a Gardner color of 4. The loss after the spent earth had been freed of oil by a naphtha wash was 0.31%. The oil recovered from the spent cake with naphtha contained no break and was not excessively dark and could be added to the next batch or the main body of oil if desired. The product underwent an alcoholysis with glycerol in the presence of litharge with no poisoning effects.

Example 3

One hundred parts of crude soybean oil (0.38% free fatty acids, 10.5 Gardner color, 135.0 I. V.) and giving a positive break test was treated with

5

7.7 parts of 8% alkali solution for 30 minutes at room temperature and heated to 65° C. Then 7.12 parts of 15% sulfuric acid solution was added and inert gas (CO_2) was bubbled into the mixture and the temperature raised to 110° C. Two parts by weight of an acid activated bleaching earth was added and agitation continued for 30 minutes. The mixture was filtered and a break-free oil with 1.90% free fatty acids, a Gardner color of 4.5 resulted. A loss of 0.28% resulted if the filter cake was washed free of oil with naphtha. The oil washed from the cake was of good color and break-free. The product reacted properly with glycerol in the presence of litharge showing that the catalyst poisons had been eliminated or rendered innocuous.

15

Example 4

One hundred parts of crude soybean oil (0.63% free fatty acids, 13 Gardner color, 131.9 iodine value) and giving a positive break that was treated with 8.4 parts of 8% alkali solution at 65° C. for 30 minutes and then acidified with 10.32 parts of 15% sulfuric acid. The temperature was raised to 110° C. and held there until the mixture was dry. The oil was allowed to cool and the inorganic salts filtered. The loss of material remaining on the cake was 1.51% of the oil after entrained oil was removed as a naphtha wash. As bleaching earth was not used, the color of oil was only slightly improved, but it was break-free and underwent an alcoholsysis readily. The final free fatty acid content was 3.20%.

Example 5

One hundred parts of solvent extracted partially degummed soybean oil (0.30% free fatty acids, 10 Gardner color, 136.8 I. V. and a positive Gardner break test) was treated with 1.8 parts of 8% alkali for 30 minutes at room temperature. The temperature was raised to 65° C. and 1.66 parts of 15% sulfuric acid solution was added. The mixture was dried by heating to 110° C. and filtered. The resultant oil was break-free and had a free fatty acid content of 0.55%, but as no bleaching earth was used was the same color as the original oil.

Example 6

A sample of crude cottonseed oil (I. V. 110.2, F. F. A. 1.03%, 13 Gardner color, and a positive Gardner break test) was treated with 8.3% by weight of a 12° Bé. caustic soda solution. The mixture was stirred at 25° C. for 30 minutes and then heated to 65° C. and stirred for 30 minutes. The mixture was then acidified with 7.66% of 15% sulfuric acid solution and allowed to settle. The lower aqueous layer was withdrawn and the oil layer washed twice with warm water. Separation of oil and water layers occurred quickly and cleanly. The oil was then dried and after clarification by filtration had a negative break test and a Gardner color of 10.5. The oil was then bleached at 110° C. with 3% of acid activated earth, to yield a final oil with a Gardner color of 6-7, 2.07% F. F. A., and a negative break test.

The loss experienced with crude cottonseed oil was found to be in the neighborhood of 0.50% if oil was recovered from the spent earth.

Example 7

One hundred parts of a crude hydraulic pressed linseed oil (1.05% F. F. A., a positive Gardner break test, and 10 Gardner color) was treated

5

with 6.2 parts of 8% alkali solution at 25° C. for 30 minutes. The mixture was heated to 65° C. and 5.74 parts of 15% sulfuric acid was added with stirring. The mixture was then dried by heating to 110° C. and three parts of an acid activated bleaching earth was added and steam introduced. The mixture was stirred 30 minutes with steam and 15 minutes to dry the mixture and then filtered. The gross oil loss was 2.27%, but if the oil on the earth were recovered, the net loss was only 0.31%. The oil recovered from the earth could be added to the major fraction or to the next batch. The final oil had a Gardner color of 6, a free fatty acid content of 1.87%, and a negative break test.

10

Example 8

One hundred parts of crude expeller linseed oil was treated with 5.8 parts of 8% alkali, 5.36 parts of 15% sulfuric acid, and three parts of bleaching earth as described above in Example 7. The original oil had a Gardner color of 12, a F. F. A. content of 0.80% and a positive break test. The final oil has a Gardner color of 5, 1.49% F. F. A., and a negative break test. The loss, if mechanically held oil on the spent earth was removed with naphtha, was 0.48%.

The steps of decolorizing the oil is not required where the oil is inherently of light color or if a light colored product is not demanded. Any surface active adsorbent may be employed in decolorizing. Acid activated clays such as are employed in the mineral oil and other industries, fuller's earth and the like are examples.

The oils of the examples could be admixed with driers, e. g. 1 to 5% lead cobalt or manganese oleates or naphthenates to make paints and varnishes. They could be fractionated by the technique of Freeman Patent 2,200,391 to obtain high iodine value and low iodine fractions. They could be cooked with phthalic acid and glycerine in place of conventionally alkali refined oils to provide alkyds of any desired oil length and were not poisonous to the catalysts.

It is a feature of the invention that the gum and break constituents of the oil are removed or converted by the combination of steps to an innocuous form in which they will not separate when the oil is heated to break temperature and they will not poison such catalysts as litharge. The advantages of alkali refining are thus secured with little or no loss of valuable oil as foots or soapstock.

The forms of the invention herein shown and described are to be regarded merely as exemplary, and it will be apparent to those skilled in the art, that numerous modifications may be made therein, without departure from the spirit of the invention or the scope of the appended claims.

60

I claim:

1. A method of treating oil containing break constituents for purposes of overcoming a tendency to produce break, which process comprises treating the oil with an alkali, then further treating the oil with a strong acid in an amount approximately equivalent to the total alkali with which the oil was treated and subsequently removing the resultant salt of the alkali and the acid.

2. In a process of treating a glyceride oil containing break constituents, the steps which comprise treating the oil, first with a small amount of caustic soda in solution in water, then with a strong acid equivalent in amount to the total caustic soda introduced, drying the oil and filter-

75

ing off the salts of the caustic soda and the strong acid.

3. In a process of treating a glyceride oil containing break constituents, the steps which comprise treating the oil with a small amount of an alkali adapted to react with the break constituents of the oil, then subsequently adding a strong acid in an amount equivalent to the total alkali added and removing the resultant salts of the alkali and the acid, and drying the oil.

4. A process as defined in claim 3 in which the amount of alkali is in excess of .01%.

5. A process as defined in claim 4 in which the oil after addition of the acid is treated with an adsorbent as a bleaching agent.

6. The steps as defined in claim 3, in which the removal of the salts is effected by water-washing the oil.

7. The steps as defined in claim 6, in which the oil treated is linseed oil.

8. A method of forming a break negative oil from oil containing break constituents, which process comprises adding to the oil approximately .01 to 1% of alkali as a water solution, then adding a strong mineral acid in an amount equivalent to the alkali added and removing the salts of the mineral acid and the alkali from the oil.

9. A method of treating soya bean oil containing break constituents for purposes of overcoming the tendency of the oil to produce break when heated, which method comprises adding to the oil .01 to 1% of caustic soda as a water solution, agitating the mixture to effect thorough contact between the oil and the caustic soda, then adding a strong mineral acid in an amount equivalent to all of the caustic soda added, and removing the

resultant salts of the strong mineral acid and sodium.

10. A method of treating soya bean oil containing break constituents for purposes of overcoming the tendency to produce break when the oil is heated, which method comprises agitating the oil with .01 to 1% of caustic soda at a temperature of 50 to 100° C. until the oil is thoroughly contacted with the caustic soda, then adding a strong mineral acid in an amount equivalent to all of the caustic soda added, drying the oil and removing the salts of sodium and the strong mineral acid therefrom.

11. A process as defined in claim 10 in which the oil is subsequently bleached by contacting it with an adsorbent clay.

12. A process as defined in claim 10 in which the oil is subsequently bleached by contacting it with an acid activated clay.

13. A process as defined in claim 10 in which the oil is subsequently bleached by contacting it with fuller's earth.
